UNITED STATES PATENT OFFICE

ROY R. WILEY, OF BUFFALO, NEW YORK, ASSIGNOR TO FLEXLUME CORPORATION, OF TONAWANDA, NEW YORK, A CORPORATION OF NEW YORK

ELECTRIC SIGN

Application filed May 2, 1928. Serial No. 274,459.

This invention relates to improvements in electric signs of the kind which utilize electroluminescent display tubes and the invention is characterized by display units, each including such a tube.

As heretofore constructed each sign has been made as a special job and it has been necessary to do all of the work from the beginning in each instance. Such a course is opposed to manufacturing economy and the resultant sign structure has been one which has presented grave problems of service and maintenance. In fact maintenance has been virtually limited to such a zone as could without burdensome expense be served from the factory where the sign was built.

The principal objects of the invention are to provide a sign of the kind described which may be manufactured on a standardized basis, that is to say a sign which as to electroluminescent letters may be composed of stock units and which is otherwise so constructed that standardized methods of manufacture may be applied; and also to provide a sign which may be readily serviced and maintained, regardless of the distance of the place of its location from the factory where it was made.

Further and specific objects are:

To embody in a sign construction one or more electrical connector receptacles which are connected to a source of electrical energy whereby the terminals of the display units may be plugged into or disengaged from the said receptacles in order to effect the electrical connection or disconnection of the display units:

To provide a construction such that the electrical connection or disconnection of the unit is effected by the same manipulation or movement as is required to place the unit on, or remove it from the supporting structure:

To enable the display units to be placed quickly and securely upon or readily removed from the supporting structure:

To provide a sign which utilizes display units adapted for manufacture in standard sizes so that the characters are interchangeable:

To maintain the high voltage lines within

the sign casing and to enclose all high voltage connections so as to prevent any person accidentally coming into contact with the electrical connections when changing a display unit or otherwise.

Stated generally the invention contemplates a sign having a supporting structure provided with one or more electrical connector receptacles which are connected to a source of power in combination with one or more electroluminescent display units provided with cooperating connector receptacles by which the units may be connected to power when placed on a supporting structure. The display face or faces of the sign may be provided wholly by the display units or partly by said units and partly by wall elements carried by the supporting structure. This structure has a generally rectangular cross section and serves some of the purposes of a casing for which reason it may be conveniently referred to as such.

A sign in which the features of the invention are incorporated is illustrated in the accompanying drawings in which:

Figure 1 is a side elevation;

Figure 2 is a plan view;

Figure 3 is a vertical longitudinal section;

Figure 4 is a cross section on the line 4-4 of Figure 3; which section is taken through the offset portion 30 of the display wall shown in Figure 5.

Figure 5 is a fragmentary horizontal section;

Figure 6 is a fragmentary section showing a detail of the connections between a display unit and the casing, which section is taken on either side of the offset portion 30.

The sign illustrated comprises a casing 1 having opposed display faces 2, each of which is formed with a series of openings 3 into which individual display units may be conformably fitted. A suitable reinforcing framework is incorporated with the casing 1 and as shown comprises a pair of vertical angle bars 4 and a pair of horizontal angle bars 5. The rectangular frame composed of these bars is arranged vertically at the longitudinal center of the casing. The sign illustrated is of the double face or projecting type 100

- and preferably has the horizontal bars 5 extended beyond an end wall of the casing and the vertical bar 4 which is adjacent the opposite end wall of the casing extended beyond 5 the upper and lower walls of the casing, the projecting ends of said bars being available for cooperation with the hanging rig by which the sign is supported from the wall of a building.
- 10 The casing carries one or more connector receptacles 6 preferably formed to provide for the complete enclosure of the terminals in porcelain or other suitable insulating material. Each receptacle has, of course, the 15 usual slots into which the projecting terminals of a companion receptacle carried by a display unit 11 may be inserted and the number of receptacles 6 corresponds to the number of display units. The receptacles as 20 shown and preferred are double but single receptacles may be employed if so desired.

While the receptacles may be carried by any suitable support an inner casing, as 7, is preferred for this purpose in order that the 25 connections between the receptacles may be completely enclosed. The receptacles 6 are fitted and held in recesses formed in the casing 7, preferably in a manner such that the slot formed portions of the receptacles project from the inner casing toward the display 30 unit receiving openings 3. The casing 7 may be supported in any suitable manner. As shown it is secured to vertical bars 8, which in turn, are secured to the frame bars 35 5. The casing is formed with suitable apertures through which the feed lines 9 extend for connection to the high voltage power lines or to the transformer.

The transformer 10 may be arranged with 40 in or without the casing 1 as desired. By locating the transformer within the casing 1 or enclosing it adjacent said casing, the necessity of outside high voltage power lines is avoided and the safety factor of the construction increased. To this end I may place the transformer within a casing 1a supported upon the top part of the casing 1. The casing 1a may either be a part of the casing 1 or 45 separate from it but in any case the transformer chamber communicates with the interior of the casing 1 to permit the feed lines which extend between the receptacle casing 7 and the transformer to remain enclosed.

The display units 11 each include an electroluminescent tube 12 and a body which 50 carries said tube and is attachable to the supporting structure. Each tube 12 is in the outline of a desired letter, character or the like and has offset portions 13 which terminate in undeturned electrode carrying 55 portions 13a. These are embedded and thereby anchored in a mass of insulating material 14, which fills a supporting casing 15. The filling 14 is preferably both electrical 60 and heat insulating and may be a hard set-

ting plastic material which adheres to the walls of the casing or a compacted granular material which is otherwise firmly confined in the casing, a sufficient quantity being utilized to completely surround the undeturned portions 13a and part of the offset portions 13. The base or bottom wall of the casing 15 is formed with an opening which aligns with a connector receptacle 16 set within the casing 15 and secured to the base thereof by fastenings 16a. The receptacles 16 are companion to the receptacle 6 and are each provided with terminals which are electrically connected to the electrodes of the tube 12 and which project into a socket or plug 70 receiving chamber. The slot formed portions of the receptacles 6 constitute plugs which are inserted through the openings of the bases of the casings 15 and into the sockets of the receptacles 16, the terminals of which 75 extend into the slots of the receptacles 6 and engage the terminals of the latter.

The exposed wall 17 of the casing 15, that is to say the wall opposite the base or bottom of said casing and which provides part 80 of the display face of the sign, is separable from said casing and is also of sectional form in order to permit it to be readily attached to or removed from the casing without disturbing the tube. The sections may have 85 any suitable arrangement or may be provided in any required number. They are articulated as at 17a by a tongue and groove joint and adjacent sections are formed with matching recesses to provide openings through 90 which the offset parts of the tube may extend into the casing. The side and end walls of the casing are formed with marginal flanges to which the wall 17 is secured by suitable fastenings 17b.

The casing 15 with the means for the securement of the unit thereto constitute the unit body by which the tube is carried and which, as attachable to the supporting structure, provides for incorporating the tube as 105 a part of the sign.

The walls of the openings 3 in which the units 11 are positioned are preferably specially formed for securing cooperation with said units. To provide the openings 3 the display walls of the casing 1 are formed as frames having upper and lower sections 18 and 19 and side sections 20 and 21. A channel member 22 is secured to the upper section 18 with its channel located behind said section and an abutment member 23 is secured to the lower section 19 with its abutment part located inward of said section. The members 22 and 23 extend continuously between the side sections 20 and 21. Abutment members 24 are secured to said side sections and the openings 3 are otherwise completely delimited by intermediate division bars 25 arranged at suitable intervals and having abutment flanges 26 similar to those of the abut- 110 120 125 130

ment members 24. The bars 25 are suitably secured at their upper and lower ends to the members 22 and 23.

The display wall 17 extends for a suitable 5 distance beyond the side and end walls of the casing 15 in order to provide for the securing of the unit to the supporting structure. The lower edge of the display wall is formed with an inturned flange 27 which 10 cooperates with the abutment member 23, the side edges of the display wall are formed with inturned flanges 28 which cooperate with the vertical abutment elements 24 or 25 as the case may be and the upper edge of 15 the display wall is formed with an offset flange 29 which cooperates with the channel of the member 22. The member 23 is peened outward at the center of each opening 3 to provide recesses 30, each for cooperation with 20 a latching finger 31 mounted on the display wall 17.

When a display unit is to be placed on a supporting structure its upper flange 29 is placed against the rear wall of the channel 25 of the member 22 and, the unit, being at such time held in a tilted position, is moved into the opening 3, the flange 29 at the same time being manipulated into the channel of the member 22 and the flanges 27 and 28 coming 30 to rest against their associated abutment parts. Thereupon the latching finger 31 is turned to engage in the recess 30 and positively hold the unit in position. As the units are thus moved into the openings 3 their receptacles come into engagement with the receptacles 6 in the manner above described. As positioned in the openings 3 the display faces of the front walls of the unit are flush with one another, with the display faces of 40 the surrounding frame 18, 19, 20 and 21 of the supporting structure and with the exposed faces of the bars 25.

The units may, of course, be removed by reversing the operations stated.

45 Where by reason of the derangement of any part of a unit a replacement becomes necessary it is of advantage to use the display wall 17 of the original unit as a part of the replacement unit and thereby complete the 50 original display face of the sign intact. This can readily be done because of the ease with which the display wall 17 can be removed from one unit and applied to another unit of corresponding size and form. Furthermore, if the unit removed by reason of derangement is to be serviced and no replacement units are immediately available, the display wall 17 can be removed, fitted together and placed on the supporting structure 55 60 to cover the opening 3, from which the unit was taken, thereby maintaining the continuity of the display face and protecting the interior of the sign from the elements.

The invention is, of course, susceptible of 65 embodiment in forms which may differ

structurally in various respects from the single form herein shown and specifically described and which may embody various alterations or modifications of or departures from the specific features of the sign illus- 70 trated.

Having fully described my invention, I claim:

1. In an electric sign, in combination, a supporting structure having connector receptacle means connected to a source of electrical energy and a display unit comprising an electroluminescent tube, a casing removably attachable to said supporting structure, insulating material in said casing, said tube having terminal portions embedded in said insulating material, and connector receptacle means carried by said casing for engaging cooperation with the first named receptacle means when the casing is mounted on 85 said supporting structure.

2. In an electric sign, in combination, a supporting structure having a display face formed with openings, connector receptacle means carried by said supporting structure 90 in line with said openings and connected to a source of electrical energy, display units shaped to be fitted in said openings and each including a display wall to cover an opening and an electroluminescent tube located beyond 95 said display wall, means for the connection of each tube to corresponding elements of said receptacle means and means for the removable attachment of each unit to said supporting structure.

3. In an electric sign, in combination, a supporting structure having a display face formed with openings, connector receptacle means carried by said supporting structure in line with said openings and connected to a 105 source of electrical energy, display units shaped to be fitted in said openings and each including a display wall to cover said openings, an electroluminescent tube located beyond said display wall and connector receptacle means behind said display wall for connection to elements of said connector receptacle means first named and means for the removable attachment of each unit to said supporting structure.

4. In an electric sign, in combination, an outer casing having a display face formed with openings, an inner casing supported within said outer casing, connector receptacle means mounted in said inner casing and exposed through a wall thereof, said receptacle means being in line with said openings and connected to a source of electrical energy, display units shaped to be fitted in said openings and each including a display wall to 120 cover said opening, an electroluminescent tube located beyond said display wall and connector receptacle means located behind said display wall for engagement with elements of said connector receptacle means first 125 130

named, and means for the removable attachment of each unit to said outer casing.

5. In an electric sign, in combination, a supporting structure having connector receptacle means adapted for connection to a source of electrical energy and a display unit comprising a casing removably attachable to said supporting structure, an electroluminescent tube carried by said casing, the terminal portions of said tube extending within said casing, and connector receptacle means carried by said casing for engaging cooperation with the first named receptacle means when the casing is mounted on said supporting structure.

15. In testimony whereof I hereby affix my signature.

ROY R. WILEY.
